UNITED STATES PATENT OFFICE.

WALTER WILLIAM WHITE, OF HIGH HOLBORN, LONDON, ENGLAND.

SEPARATION OF VOLATILE PRODUCTS FROM SOLID CARBONACEOUS MATERIAL.

1,257,772.

Specification of Letters Patent. Patented Feb. 26, 1918.

Application filed September 1, 1916. Serial No. 118,004.

To all whom it may concern:

Be it known that I, WALTER WILLIAM WHITE, a subject of the King of Great Britain, residing at 125, High Holborn, in the county of London, England, have invented certain new and useful Improvements in or Relating to the Separation of Volatile Products from Solid Carbonaceous Material, of which the following is a specification.

This invention relates to an improved continuous process and improved apparatus for the separation of volatile products from solid carbonaceous material such as coal, shale, peat and the like passed through a progressively heated retort chamber, in which process vapors produced at different temperatures are withdrawn immediately from the heated material into a separate vapor chamber, enabling the oils and other condensable substances to be gradually deposited in the said chamber without the necessity of cooling the vapors to a low temperature.

According to this invention the vapors produced from the heated carbonaceous material at higher temperatures and withdrawn into the aforesaid separate vapor chamber are led in succession through the lower temperature vapors in such a manner as continuously to deposit their condensable ingredients in the said chamber by the action of the successively cooler vapors. Each body of vapor drawn off at the lower retort temperature thus forms a curtain of cooler vapor for the portion or portions given off by the material at a higher temperature or temperatures and the complete operation proceeds continuously, the material in the retort traveling constantly from a cold inlet through increasingly heated zones, while the separated vapors have a reverse flow, those produced at the hotter zones traveling continuously through progressively cooler zones to an outlet at the cold end of the vapor chamber where the uncondensed gases and vapors escape, while the condensed liquids deposit in the vapor chamber and are drawn off at any convenient point or points at or near the cool end.

In order that the said invention may be clearly understood and readily carried into effect the same will now be described more fully with reference to the accompanying drawings, in which:

Figure 1 is a longitudinal section, with

parts in side elevation, of a retort apparatus and furnace embodying this invention;

Fig. 2 is part end elevation and part cross section and Fig. 3 a plan of a portion of the complete installation, including two pairs of retort tubes.

A, A are horizontal or nearly horizontal retort tubes receiving the carbonaceous material, which is carried along the tubes by screw conveyers B. C is the furnace in which the retorts are heated by means of the gas jet D placed at or near the discharge end. E, E are the vapor condensing tubes or receivers placed above and between each pair of retort tubes, with which they communicate at different points along their length by means of the connecting pipes e, e', e'', e'', e'', the tubes E having at their cool end the gas and oil outlets e'' and e''. The said tubes are horizontal or practically so, but may have a very slight tilt toward their outlet end to facilitate the flow of the condensed oils.

The carbonaceous material to be distilled is fed to the retort tubes through the hoppers F, each hopper having a rotary feeding valve f' operated by chain gearing f' from the shaft b of the screw conveyor, which shaft is rotated intermittently by the hydraulic ram or motor G acting through an arm g and pawl g' on a ratchet wheel b' on the said shaft. At the coke discharge outlet H (Fig. 1) is a rotary discharge valve h driven by the chain h' from the discharge end of the conveyor shaft b, so that the inlet and discharge operations proceed steadily under the same control.

The retort tube is heated at a progressive temperature from the inlet end to a point situated beyond the last connecting pipe e'' leading to the condensing tube E. It is found that this progressive heating can be effected by the single jet D supplied with gas (which may be that produced in the apparatus itself) and preferably with hot air heated by the waste heat from the furnace. The hot gases from the furnace chamber c containing the jet D pass up through the perforated firebrick floor c', thence into the space c'' (Fig. 2) surrounding the retort tube and, after flowing along the retort tube toward the inlet end, escape through the flue c'' into the main flue c*. As the temperature of the gases is steadily falling toward the flue c* the tube A is only moderately heated

near the inlet end, the temperature progressively increasing from this end.

The condensing tubes E are outside the furnace proper, but are situated so that unduly rapid cooling of the vapors is avoided. The tubes also extend for some distance beyond the inlet end of the retorts, this extended portion, clear of the furnace casing, serving for the final condensation of the liquefiable part of the vapors.

The general operation of the apparatus is as follows:

The coal or other carbonaceous material is fed at regular intervals into the inlet end 15 of the retort tube from the hopper F, the feeding valve f preventing gases from the retort escaping through the hopper. The screw conveyer B, driven by small regular intermittent movements, takes the material 20 from the inlet and gradually through all the zones of increasing temperature, the volatile constituents being progressively driven off until the remaining solid material discharged at H contains only a small proportion 25 of the volatile ingredients, the proportion depending upon the maximum temperature attained—say about 600° C.—and the rate at which the material is passed through the retort. As the material passes 30 through the low temperature zone of the retort, water and any very volatile ingredients which may be present are drawn off, escaping into the condensing tube or chamber E from the retort tubes A at each side 35 through the first of the connecting pipes e to e'. As the material travels into hotter zones, volatile ingredients having higher temperatures of vaporization are driven off and are promptly removed, close to their 40 place of origin, by the adjacent pipes e to e' into the relatively cool chamber E. The vapors therefore remain only for a very short time in the hot retort tube and are removed before any appreciable "cracking" 45 can take place. Five pipes e to e' are shown for each retort tube A, but a greater number may be employed, or the retort and condensing tubes may be otherwise placed in practically continuous communication 50 along their length so that the vapors are withdrawn from the retort tubes very close to the place of origin.

It will be seen that as the vapors are drawn through the condensing tube or collector E toward the gas outlet e⁵, the vapors given off at higher temperatures must pass through the progressively cooler vapors generated in the cooler zones of the retort. Thus the liquefiable ingredients or oils are 55 caused gradually to condense and to fall to the bottom of the tube E, where they collect and flow toward the oil outlet e⁶ from which they are withdrawn. The cooler vapors therefore act as the condensing agent 60 for the liquefiable ingredients in the vapors

driven off in the hotter zones and the whole process of distillation and condensation proceeds in a steady, continuous manner with the maximum economy of heat.

What I claim and desire to secure by Letters Patent of the United States is:—

1. The process for separating condensable volatile products from solid carbonaceous material distilled in a retort, which consists in heating the material to a graduated temperature, withdrawing the distilled vapors arising at different temperatures from contact with the solid material, leading the separated vapors distilled at higher temperatures through the separated vapors distilled 75 at lower temperatures to cause condensation and removing the liquefied volatile matter from the uncondensed vapors, the condensation taking place out of contact with the said solid material.

2. The process for separating condensable volatile products from solid carbonaceous material distilled in a retort heated to a graduated temperature, which consists in moving the solid material through zones of increasing temperature, withdrawing from contact with the solid material the distilled vapors arising at different temperatures, leading the separated vapors in a direction opposite to that of the movement of the 90 solid material so that the separated vapors produced at higher temperatures pass through and are condensed by the separated vapors produced at lower temperatures, and removing the liquefied volatile matter from the uncondensed vapors, the condensation taking place out of contact with the said solid material.

3. The process for separating condensable volatile products from solid carbonaceous material distilled in a retort heated to a graduated temperature, which consists in moving the solid material through zones of increasing temperature, separately withdrawing from contact with the solid material the distilled vapors arising at a succession of stages in the travel of the said material, leading the separated vapors in a direction opposite to that of the movement of the solid material so that the separated vapors produced at higher temperatures pass through and are condensed by the separated vapors produced at lower temperatures, and removing the liquefied volatile matter from the uncondensed vapors the condensation taking place out of contact with the said solid material.

4. In apparatus for separating volatile products from solid carbonaceous material, a retort, means for heating the retort to a graduated temperature, means for conveying the solid material through the retort, a vapor collecting and condensing chamber communicating with the said retort at stages along the length of the latter, an outlet for 125

the uncondensed vapor situated toward the end of the said vapor chamber which is adjacent to the inlet end of the retort and an outlet for the liquefied volatile matter, the vapor chamber and outlets being adapted to prevent contact of the separated vapors and their condensates with the said solid material.

5. In apparatus for separating volatile products from solid carbonaceous material, a retort, means for heating the retort to a graduated temperature, means for conveying the solid material through the retort, a vapor collecting and condensing chamber, pipes connecting the said chamber to the retort at successive points along the length of the said chamber and retort, an outlet for the uncondensed vapor situated toward the end of the said vapor chamber which is adjacent to the inlet end of the retort and an outlet for the liquefied volatile matter, the vapor chamber, pipes and outlets being adapted to prevent contact of the separated vapors and their condensates with the said solid material.

6. In apparatus for separating volatile products from solid carbonaceous material, a substantially horizontal retort tube, a conveyor in the said tube, means for heating the retort to a graduated temperature, a

parallel vapor tube, pipes connecting the said vapor and retort tubes at successive stages along their length, an outlet in the vapor tube for uncondensed vapor, situated at the end adjacent to the inlet of the retort tube, and an outlet in the vapor tube for the liquefied volatile matter, the vapor chamber, pipes and outlets being adapted to prevent contact of the separated vapors and their condensates with the said solid material.

7. The process of separating condensable volatile products from solid carbonaceous material, which consists in fractionally distilling condensable volatile products of said material, and subjecting the less volatile and hotter vapors to the cooling influence of the more volatile and cooler vapors, while out of contact with the solid residue and until condensation takes place.

8. An apparatus for separating volatile products from solid carbonaceous material, including a retort for fractionally distilling said volatile products, a condensing chamber for receiving said vapors, an outlet for said condensing chamber to receive the condensates, said condensing chamber being of such shape and capacity as to cause the less volatile and hotter vapors to be cooled by the more volatile and cooler vapors.

WALTER WILLIAM WHITE.
